UNITED STATES PATENT OFFICE.

WILLIAM ORD, OF BROOKLYN, OHIO.

CULTIVATOR.

SPECIFICATION forming part of Letters Patent No. 287,956, dated November 6, 1883.

Application filed April 21, 1883. (No model.)

To all whom it may concern:

Be it known that I, WILLIAM ORD, of Brooklyn, in the county of Cuyahoga and State of Ohio, have invented certain new and useful Improvements in Cultivators, of which the following is a specification.

My improvements relate to the construction of iron cultivators, and have for their object the production of a cheap, simple, and durable machine, whereby the farmer or user is enabled to easily and readily construct or repair his own cultivators. These improvements consist in providing peculiarly constructed and applied clamps for attaching the teeth, brackets, and braces to the frame-work, whereby the parts are held more firmly and rigidly together and in proper positions, and which allow ready adjustment of the adjusting parts when required.

In the accompanying drawings, Figure 1 is a top or plan view, Fig. 2 is a side elevation, and Fig. 3 is a rear elevation, of my improved cultivator. Fig. 4 is a detached and enlarged view of the center clamp, illustrating the manner of securing the rear ends of the side wings to the central bar and the method of adjusting said wings therewith. Fig. 5 is a detached and enlarged view of one of the corner bracket-clamps, showing manner of securing the brackets to the wing-bars and extension-bars together with the adjustable brace. Fig. 6 shows a clamp adapted for securing a curved spring cultivator-tooth. My said clamps are thus made applicable for either form or kind of cultivator-teeth.

In the several figures is the main or central bar, to which are attached two side wing-bars, B B, by a joint near the front end, in the usual way. Handle-bars C C are also permanently attached to said central bar, near its front end, and are supported by a U-shaped support. This support provides two perpendicular arms for the brace-adjusting block to slide perpendicularly upon in expanding or contracting the wings. The rear ends of said wings B B are connected to the central bar by extension-arms D D in the usual way. Said bars D D are adjustably secured to the central bar by one of my improved clamps. Said clamp consists of a lower block, b, having a longitudinal groove fitting on the under side of the bar A, and with a transverse space, for

the extension-bars D D to lie in, beneath said bar A, as seen in Fig. 4. Said block is of cast-iron, and has two bolts, d d, in two corners, diagonally across from each other. Above said block b is placed a grooved plate or cap, b², fitting over the top edge of said bar A, and has two holes for the said bolts d d to pass up through, and is secured by two nuts on top. The position of the two bolts and the arrangement of this clamp are such as to secure a firm hold on the bar and prevent its working loose and rocking. The U-shaped support is also secured by the rear nut and bolt of this clamp. The corner-clamps on the rear ends of the wing-bars B B are similar to this, but are provided with a central pin, i, over which the end of the extension-bar D sits, and said lower block is cast with the bracket, while the cap or top plate has a downward projection, b³, which rests on the top of the bar D, and it also has on the upper side an ear, e, to which is pivoted a brace-rod, E. Said brace-rod is simply joined to the clamp aforesaid, and has its upper end curved and bent and provided with a small grooved block, F, having a hole, and fitted onto the bent end of said rod, which end is also screw-threaded and provided with a thumb-nut, f. This block F fits onto the perpendicular arm of the U-shaped handle-support, the bent part of the rod forms a bearing against the side of said arm, resting in one of the notches in the support, and when the thumb-nut is screwed down the rod is firmly held in place. This rod and its clamp form an adjustable side brace for securing the wing-bars in their relative position to the main or central bar, and is very simple and easily operated.

In Fig. 6 is shown a clamp-block adapted to hold curved spring-teeth. The under side of this block is provided with a recess and two lugs, l l, having a groove in line with the sides of said recess. The end of the tooth is made a little wider at the end to give its sides a little taper, said recess also being wider at the front end. The purpose of this is to enable the tooth to be inserted and removed when desired. A screw, S, is put through a slot in the tooth for securing it to the block. The slot enables the tooth to be adjusted back in case of wear or becoming loose. By removing said screw the tooth is easily removed, as

will be seen by dotted line in Fig. 6, which is done by pushing the tooth forward until the narrow part comes between the lugs. Then the tooth may be taken out by raising one side and 5 withdrawing it from the opposite lug.

Among the advantages and the objects of my improvements are to dispense with the large number of holes that are required to be drilled in the bars in the present method of 10 constructing iron cultivators, which considerably weakens the bars, and requires much time and labor to perform. With the use of my improved clamps the time, labor, and expense of constructing, changing, and repairing is greatly reduced, and enables an ordinary 15 blacksmith or farmer to do the work himself. These clamps are complete and ready to be applied to the bars, which should have indent or notches made in their under edge 20 as guides and to indicate points at which to place them, and which also serve to prevent slipping. These clamps can be furnished to the trade in like manner to the spring-teeth for cultivator-plows.

25 It will be seen that the teeth or brackets may be adjusted to give them more or less pitch forward or back, as the bottom of the groove

in the blocks *b* is made curved or crowning, so that by loosening on one nut and tightening up on the other any required pitch may be obtained.

Having described my invention, I claim as follows:

1. In combination with the side bar, *B*, and brace *D*, the clamp herein described, consisting of the part *b*, having longitudinal groove to receive said bar *B*, transverse space to receive the brace, and lug *i*, which is received into an aperture in said brace, and the cap-plate *b*², having downwardly-extending lug *b*³, and the securing-bolts, as and for the purposes set forth.

2. In combination with the frame *U*, handles *C C*, and central bar, *A*, the clamp *b* *b*², the latter having the ears *e*, the arm *E*, block *F*, having slot to receive the standard of the said frame *U*, and set-screw *f*, for giving any desired adjustment to the side wings, as set forth.

WILLIAM ORD.
